 The Black-Clawson Company, Hamilton, Ohio,
 a corporation of Ohio

Application November 15, 1935, Serial No. 49,889

6 Claims. (Cl. 92—43)

This invention relates to the manufacture of paper, paperboard, and the like, and more particularly to cylinder mold machines therefor.

One of the principal objects of the invention is the provision of a cylinder machine having a vat surface which cooperates with the mold surface in defining the flow path of the stock to the mold surface and which is arranged to effectively alter the flow conditions in the movement of stock to the mold to obtain a wide variation in the characteristics of web formation on such a machine.

Another object of the invention is the provision, in a cylinder machine, of a means over which stock flows to the mold and including an extending portion directed toward the mold and pivotally adjustable to control the formation of webs of widely different characteristics.

Another object of the invention is the provision in a cylinder machine of a vat having a wall portion incorporating an apron which is readily adjustable to alter the stock level in the machine vat and to concomitantly vary the flow conditions of the stock to the mold.

A further object of the invention is the provision of a cylinder machine having a vat structure in which the stock flow, during its traverse of the vat, is repeatedly acted upon at successively spaced points along the effective forming zone so as to alter the lines of flow.

Other objects and advantages of the invention will be apparent from the following description, the accompanying drawings and the appended claims.

In the drawings, which disclose a preferred embodiment of the invention,—

Fig. 1 is a plan view of a cylinder mold constructed in accordance with this invention;

Fig. 2 is a fragmentary sectional view as indicated by the line 2—2 of Fig. 1;

Fig. 3 is a fragmentary sectional view as indicated by the line 3—3 of Fig. 2;

Fig. 4 is a fragmentary elevational view showing a means of adjustment;

Fig. 5 is a fragmentary sectional view taken similarly to Fig. 2 and showing a somewhat different form of the adjustable structure;

Fig. 6 is a fragmentary sectional view taken perpendicularly to the mold axis, and somewhat diagrammatic in character, showing an arrangement of the vat structure that is repeatedly effective on the stock flow as it traverses the vat;

Fig. 7 is a view taken similarly to Fig. 6 showing a somewhat different arrangement for repeatedly influencing the stock flow; and

Fig. 8 is a sectional view of a cylinder machine

showing a further modification in the vat structure.

The conditions of stock flow in cylinder machines is an important factor in the determination of the characteristics of a paper web formed thereon. That is, by altering the depth and direction of stock flow, and the speed of flow with respect to the rate of travel of the mold surface, webs having widely varying characteristics may be formed. In explanation of the term varying characteristics, and as an example of characteristic differences, it is pointed out that in some instances it may be desirable to form a web having a greater strength in one direction, while for other purposes a web of substantially uniform strength in all directions is desirable, or sheets of different thickness and of different maximum strength may be desired. Through the practice of this invention webs of widely varying characteristics can be formed in a single machine, only a simple adjustment being required to alter the machine to produce a web of the particular characteristics desired.

Referring now to the drawings, in which like characters of reference designate like parts throughout the several views thereof, a cylinder machine is illustrated comprising a vat 10 enclosing a cylinder mold or forming surface 11 having suitable supporting structure and flow connections common to such machines and known in the art. Stock is admitted to the machine through an inlet 12 adjacent an end of the vat remote from the mold 11 and flows upwardly within confining walls of which one inclined wall 13 is shown as merging into an apron 14 which has a transversely extending wall portion 15 over which the stock flows toward the mold. This wall portion preferably inclines upwardly toward the mold. The inner end of the apron 14 merges into the vat wall 16 which preferably follows the contour of the forming surface 11 of the mold.

In the form of the invention illustrated in Fig. 2 the apron 14 is shown as a casting portion which extends across the vat and is suitably supported from the vat side walls as indicated at 18. That portion of the apron portion remote from the mold 11 is curved downwardly as indicated at 19 and forms a smooth flow surface continuing from the inlet wall 13. The portion 20 of the apron casting which lies adjacent the mold 11 extends downwardly to the curved vat wall 16.

At that part of the apron portion or wall 15 where the stock flow approaches the mold there is provided adjustable means whereby the direction and depth of the stock flow may be readily

controlled to thus alter the characteristics of the formed web by influencing the positioning of the fibers in the stock flow. As shown, at the junction of the apron wall 15 and the upwardly extending wall portion 20 there is provided a movable member which is adjustably mounted so that it may be swung into a desired one of a plurality of positions; each differently effecting the stock flow to the mold.

10 Referring more particularly to Figs. 1 to 4, the movable member is shown as comprising a blade 22 mounted upon a cylindrical member that is pivotally supported on the vat walls and which lies within a recess formed by the wall portion 15 in the apron adjacent the junction of the wall portions 15 and 20. The cylindrical member, which is indicated by the numeral 23 and which is preferably constructed as a tube, as shown, extends for the full width of the vat; suitable 15 supporting means being provided in the vat walls whereby this member may be rocked to afford a desired positioning of the blade.

To prevent undesired interruption to the stock flow the apron recess for the blade supporting member 23 is so proportioned that the upper part 25 of the member 23 lies substantially in the plane of the apron face 15. The gap between the member 23 and the curved wall 25 which defines the recess is covered by a thin flexible plate 26 which 30 is attached to the apron face 15 some distance from the member 23 and continues beyond the gap a sufficient distance to overlie and contact with the cylinder part 23. The blade 22, which may be formed from a brass plate, is attached to 35 the tubular member 23 as by brazing and is positioned so that its upper face bears a tangential relationship to the surface of the member 23. Suitable stiffeners or brace members 27 are provided to further strengthen the blade 22. 40 By assembling the blade to the member 23 in the manner shown a smooth surface can be afforded having no breaks or interruptions to adversely affect the stock flow.

For support of the blade assembly each end of 45 the tube 23 has a close fitting plug 30 which is provided with an axial opening to receive a shaft extension which may be held therein as by means of set screws. As is shown in Fig. 3, the shaft extension 31 at one end of the tube is received 50 within a bearing cap 32 positioned on the outside of the vat side wall. The opposite end of the tubular supporting member 23 has a shaft extension 34 which extends through the vat side wall and through a supporting bearing 35 incorporating 55 a packing gland 36 to prevent leakage from the vat at this point. Additional support of the tube 23 is afforded by a block 37 of suitable bearing material such as babbitt which is placed within the apron recess intermediate its ends and 60 is shaped to contact the curved face of the underside of the part 23.

Control means are provided to permit adjustment of the blade and to hold the blade in desired positioning. As shown, a ratchet member 65 38 is fixed to the shaft extension 34 and cooperates with a pawl 40 that serves to hold the blade assembly in desired positioning. The pawl 40, which is pivotally mounted on the stud 41, has a weighted extension 42 tending to hold the 70 pawl in engagement with the ratchet. An operating handle 44 is provided on the shaft extension and, as shown, stands parallel to the blade 22 to thus afford an indication of the blade positioning which, during service, is concealed from 75 view by the flow of stock over it.

The range of angular movement of the blade 22 (Fig. 2) is such that it may be moved from a position wherein it lies closely adjacent the wall portion 20 and stands substantially in continuation of that wall portion as is indicated by the dotted outline 22a. In this position the blade has substantially no effect on the flowing stock and serves merely as a smooth continuation of the flow defining wall over which the stock passes into the forming zone. When moved upwardly 10 to the position indicated in full lines, and wherein the blade stands substantially in continuation of the apron face 15, the effective distance through which stock may flow to contact with the forming surface of the mold is substantially 15 narrowed or reduced and consequently, because of the reduced area, the rate of flow of the stock under such conditions is materially increased at that particular point. After passing that point the speed of flow is then very rapidly reduced by 20 reason of the comparatively large space beneath the blade into which the stock whirls. This change in area and resulting change in rate of flow thus produces a stock flow at some point or points which may equal or exceed the speed 25 of the mold movement, so that the resulting web comprises a fiber mat in which the separate fibers have been interlaced to a degree that the paper web is of substantially uniform strength in all directions.

In effect, this positioning of the blade serves 30 to move the weir to a position more closely adjacent the mold than occurs with the blade in the position indicated at 22a so that a more rapid 35 rate of flow occurs for a given stock flow with the blade so positioned. In addition, the thin projecting blade serves to create a whirlpool beneath it so that a very effective intermingling of the fibers results from such a blade positioning. In those instances where it is desired to 40 raise the stock level to a point above that afforded by the apron this may be readily accomplished by a further movement of the blade so that it extends upwardly with respect to the apron surface and as defined by the dotted outline 22b. The blade range of movement is such that it may 45 be positioned to stand at a rather abrupt angular relationship with respect to the apron face so that a material increase in the stock depth is possible. Within this last mentioned range of 50 positioning the flexible plate 26 assumes a positioning such as is indicated at 26a and affords a smooth uninterrupted flow path to the end of the blade. It is to be noted that here also a whirlpool effect may be produced on the underside of 55 the blade which acts to create a random positioning of the fibers. It is further pointed out that the blade exerts its influence on the stock flow within the initial forming zone, that is, within the zone of formation in which the stock first 60 comes in contact with the forming cylinder and where the formation is most rapid.

It is apparent that through the provision of the simple movable member the operating characteristics of a cylinder machine may be altered to a 65 degree that the characteristics of a web formed thereon may be varied within wide limits. With the member turned downwardly so that it follows the contour of the vat circle it has substantially no effect on the flowing stock, and the weir, then 70 defined by the tubular supporting member 23, is some distance removed from the forming surface so that with a slowly moving body of stock a pronounced fiber alignment may occur which will result in the formation of a web having materially 75

greater strength in one direction. By moving the member to the opposite extreme of its angular range of travel the area between the forming surface and the vat circle remain substantially as before. In this position, however, the member serves to materially raise the stock level in the vat. Intermediate positions provide for varying degrees of effect on the stock flow. In those positions approaching a continuation of the apron 10 face 15 the area of stock passage at the forming surface is reduced to a point that the rate of stock flow is materially increased with the resultant effective intermingling of the fibers and production of a web of uniform strength characteristics. 15 Referring now more particularly to the slightly modified form of the invention illustrated in Fig. 5, the adjustable member or blade 22' is shown as having an extended part 50 which curves downwardly and continues as a semi-cylindrical portion for a sufficient distance to overlie the vat wall 16'. As shown, the junction of the apron 14' and the vat wall 16' is arranged to include a recess 51 within which the extending curved part 50 of the member 22' is received. The depth of the recess 25 is sufficient to accommodate the part 50 when the member 22' is in a lowered position as indicated by the dotted outline, and the part 50 is sufficiently long to extend within the recess when the member is in an elevated position. As shown, a flexible member 52 is attached to the wall 16' and bears against the part 50, thus serving as a sealing means at this point.

The flat portion 53 of the member 22' extends tangentially from the cylindrical member 23' that serves as its support and, like the blade 22 described above, is adjustable across the plane of the apron. In accordance with the constructions illustrated in Figs. 2 and 5, the stock is given a whirling action such as will thoroughly intermix 40 the fibers and cause them all to assume different directions at the point where the downturning side of the forming cylinder enters the stock. Thus the stock that is initially applied to the forming cylinder is applied so that its fibers are 45 arranged in different directions. However the formation of the stock continues beyond this initial forming zone, and some stock is deposited up to a point near the bottom of the cylinder due to the fact that the water level within the cylinder is 50 comparatively low as compared with the stock level in the vat. In order that the stock will be kept in a thoroughly mixed condition, even beyond the initial forming zone, the wall of the vat which generally follows the outline of the cylinder 55 inder itself, is provided with a series of projections or extensions that reach towards the forming cylinder, as shown for example in Figs. 6, 7, and 8. These projections are such as will influence the stock flow so as to change the speed of 60 flow at different points along the downturning side of the cylinder.

As shown in Fig. 6, the cylinder machine comprises a vat wall 16b which cooperates with the face of the mold 11b in defining the flow path of 65 the stock. At or adjacent the top of the wall 16b is a blade or projection 60, that may have a form in accordance with the construction shown in Figs. 2 or 5, or which may be a simple flat blade pivoted at its point of connection to the end of the apron surface 14b. The wall 16b is furthermore provided with a series of spaced blades, each extending the full length of the vat, and provided on the vat wall 16b between the initial forming zone and a point adjacent the bottom of the forming 70 screen. These blades, which are preferably

mounted for individual pivotal movement by means similar to the moving mechanism illustrated in Fig. 4, extend toward the forming screen far enough so as to cause a considerable change in speed at the point where the stock passes 5 between the ends of the blade and the forming screen surface, and this gives a whirling action in vertical planes along the length of the blade and below the blade. The blades 60 are provided along the entire length of the effective forming 10 zone from the initial forming point to the point where formation practically ceases, it will be apparent that the entire thickness of the paper sheet deposited on the forming screen will be of strong 15 character, its strength being controllable in accordance with the conditioning of the various blades so that the surface characteristics of the paper sheet may be made different from the characteristics of the body portion below the surface.

As above mentioned, the blades 60 in the construction shown in Fig. 6, are comparatively flat blades, either fixedly or pivotally mounted. However the blades need not be made flat, and may be made in accordance with the construction shown in Fig. 7, in which there are rounded projections 20 70 spaced apart along the entire forming zone and along the inner surface of the vat wall 16c. These projections or ridges 70 of course extend the entire length of the vat, and are fixed in position, the rounded sides of the projections producing the 25 difference in stock flow speed at different points along the forming zone, but changing the direction of the stock in a more gradual manner so as to avoid violent whirling action below the blades, and also to reduce the tendency for stock to stay 30 in one spot below or above the blades along the wall 16c. In this construction, the forming screen 11c rotates clockwise regardless of whether the stock is flowing into the vat over the dam 14 or whether the stock is flowing into the vat from the 35 opposite side thereof.

In accordance with the construction shown in Fig. 8, the inner surface of the vat wall 73 generally follows the curvature of the rotatable forming screen 11d, but the surface of the vat wall 73 45 is corrugated as by means of the corrugated sheet 74 which extends all along the downturning side of the cylinder mold and if desired along the upturning side as well, so that the velocity of the stock flowing along the surface of the forming 50 screen is changed at successively spaced points all along the length of the forming screen to give the desirable mixing action of the stock fibers in order that any tendency of the stock fibers to align themselves with the direction of flow will be 55 disturbed at successively spaced points throughout the entire forming area.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A cylinder machine comprising a cylinder mold and a vat therefor, an apron portion in the vat comprising an upper wall portion over which the stock overflows toward the mold terminating at a wall portion following the contour of the 70 mold, said apron portion having a recess extending thereacross between the said wall portions, a rotatably movable member of substantial size extending across the vat within and substantially filling said recess, and a blade extending from the 75

rotatable member and adapted to adjustably vary the flow conditions of the stock upon movement of said rotatable member.

2. A cylinder machine comprising a cylinder mold and a vat therefor, an apron portion in the vat comprising an upper wall portion over which the stock overflows toward the mold terminating at a wall portion following the contour of the mold, said apron portion having a recess formed 10 between the said wall portions, a member extending across the vat and rotatably mounted thereon, said member lying within the apron recess, a blade extending tangentially from said member and movable therewith, said blade standing in one 15 adjusted position so that its upper surface is substantially in continuation of the upper wall portion of the apron portion.

3. A cylinder machine comprising a cylinder mold and a vat therefor, an apron portion in the 20 vat opposite the downturning side of the mold comprising an upper wall portion over which the stock overflows toward the mold terminating at a wall portion following the contour of the mold, said apron portion having a recess extending in a 25 direction parallel the mold axis and between the said wall portions, a rotatably mounted member extending across the vat and having a cylindrical portion concentric with its axis of rotation adapted to be positioned within said apron recess, a 30 blade extending tangentially from the upper side of the member toward the mold and movable therewith to a position in which the blade stands in flush relationship with one of the apron wall portions.

25 4. A cylinder machine comprising a cylinder mold and a vat therefor, an apron in the vat comprising a generally horizontal upper wall portion over which the stock overflows toward the mold and terminating at a wall portion following the 40 contour of the mold, said apron having a recess

formed therein extending in the direction of the mold axis intermediate the said wall portions, a rotatably mounted member extending across the vat and lying within said recess with the upper portion thereof tangentially related to the generally horizontal apron surface, a blade fixed to the member and extending for the length of said member, said blade being mounted tangential to the upper portion of the member and projecting therefrom toward the mold, and a flexible plate 10 fixed to the generally horizontal apron wall portion and overlying said member.

5. A cylinder machine of the character described comprising a cylinder mold and an open top vat in which the mold operates, said vat having a substantially horizontally disposed wall over which stock flows to the space around the mold, and a pivotally supported blade adjustable to project from said wall towards the downturning side of the mold and terminating at a predetermined 15 spacing opposite an unobstructed surface of the mold where initial rapid formation takes place.

6. A cylinder machine of the character described comprising a cylinder mold and an open top vat in which the mold operates, said vat having a substantially horizontally disposed wall provided with a stationary upper surface which extends generally towards the mold and over which stock, while freely exposed at the stock surface, overflows to the space around the mold, and an 25 adjustable mounted blade adjustable to project at various predetermined angles of inclination from said wall towards the downturning side of the mold and located at a predetermined distance with respect to an unobstructed surface of the 30 mold where rapid formation takes place to influence the speed of stock flow in the vat within the zone of initial formation.
